UNITED STATES PATENT OFFICE.

FRANK JOHNSON, OF AURORA, ILLINOIS.

AIR PUMP.

Application filed January 18, 1921. Serial No. 438,108.

To all whom it may concern:

Be it known that I, FRANK JOHNSON, a citizen of the United States, residing at Aurora, in the county of Kane and State 5 of Illinois, have invented certain new and useful Improvements in Air Pumps, of which the following is a specification.

This invention relates to air pumps and has for its principal object to generally improve upon pumps of this nature by providing a device which will be of extremely simple, durable and inexpensive construction, one which is efficient and reliable in operation, and well adapted to the purpose 15 for which it is designed.

With the above and numerous other objects in view, this invention comprises certain novel features of construction and arrangement of parts as will be hereinafter 20 more fully described.

In the drawing:—

The figure is a vertical and longitudinal section taken through the pump.

Referring to the drawings by numerals 25 it will be seen that 1 designates the base having any suitable means such as the bolt 2 for attaching same to a support. The up-standing wall 3 projects at right angles to the base 1 from its longitudinal side edges 30 and pivotally supports the pump itself. The pump itself consists of the main cylinder 4 and the auxiliary cylinder 5 which has a diameter smaller than that of the main cylinder. These cylinders extend longitudinally 35 of each other and are in communication with each other having the valve seat 6 situated therebetween. A piston 7 is movably mounted in the main cylinder 4 and is fixed in any suitable manner to the piston 40 rod 8. The end of this piston rod 8 extends a distance into the auxiliary cylinder 5 and is threaded so as to be connected to the rod 9 which is integral or otherwise fixed to the auxiliary piston 10 which is movable in the 45 auxiliary cylinder 5.

A valve 11 is slidably mounted on the rod 8 and a suitable washer 12 is disposed between the valve 11 and the valve seat 6. This valve 11 is cup-shape so as to form 50 thereon a stuffing box 13. Suitable packing 14 is situated therein and firmly held by the gland 15. An annular groove is provided in the stuffing box 13 in which fits the wire 16 by abutting the valve seat 6 thus limiting 55 the movement of the valve 11 from this valve seat.

Particular attention is called to the construction of the pistons 7 and 10. The active faces of these pistons are cut away so as to form a dove tailed annular shoulder 17 60 for receiving the concavo-convex leather washer 18. It will also be noted that the main piston 7 is slightly spaced from the main cylinder 4 so that air may pass therebetween as the piston 7 is pushed to the right 65 as shown in the drawing.

An operating lever 19 is pivotally mounted on the base 1 and is pivoted intermediate its ends to the rod 9. Upon operation of the lever 19 it will be seen that when same is 70 pushed to the left the rod 9 will also be pulled to the left thus moving pistons 10 and 7. Upon movement of the piston 7 to the left the air contained in the cylinder 4 will be compressed and will force the valve 75 11 to an open position so that the air will fill up the auxiliary cylinder 5 as the piston 10 is being moved to the left. Owing to the fact that the capacity of the auxiliary cylinder 5 is smaller than that of the main cylinder 4 it will be readily seen that some of the air will be forced through the outlet 20 which may be of any preferred construction. After the piston 7 has come into engagement with the valve seat 6 and this end 80 of the cylinder 4 the lever 19 will then be pushed to the right. The air which has been forced into the auxiliary cylinder 5 will now be compressed by the pistons 10 and will force the valve 11 to close and force the air 85 through the outlet 20. In the mean time the air will be replenished in the main cylinder 4 since it will be allowed to enter through the space between the piston 7 and the inner wall of the main cylinder 4. It will be readily seen by an inspection of the drawing, however, that this air can only pass by the piston 7 when it is traveling to the right or upon its non-compression stroke. Attention 90 is also called to the cylindrical cavity 21 100 which is provided centrally in the piston 7 so as to accommodate the stuffing box 13 and gland 15, when the piston 7 is moved completely to the left.

From the foregoing description, taken in 105 connection with the accompanying drawing, the construction and operation of the device will be readily understood without a more extended explanation. As numerous changes in form, proportion, and in the minor details of construction may be resorted to without departing from the spirit of the in-

vention, I do not wish to be limited to the construction herein shown and described other than as claimed.

Having thus described my invention what I claim as new is:—

1. In combination, a main cylinder, an auxiliary cylinder of smaller diameter than the main cylinder and situated so as to extend longitudinally therefrom and in communication therewith, said auxiliary cylinder provided with an outlet adjacent the main cylinder, a check valve situated in the outlet, a main piston movable in the main cylinder and slightly spaced from its inner wall, means carried by the main piston for allowing air to pass between the piston and the wall as the piston moves away from the auxiliary cylinder, an auxiliary piston movable in the auxiliary cylinder, a second check valve constructed so as to allow a fluid to pass from the main cylinder to the auxiliary cylinder only, means for connecting the two pistons, and means for operating the pistons.
2. In combination, a main cylinder, an auxiliary cylinder of smaller diameter than the main cylinder and situated so as to ex-

tend longitudinally therefrom and provided with an opening communicating therewith, an outlet check valve situated in the auxiliary cylinder adjacent the main cylinder, a check valve slidable in the opening between the main cylinder and the auxiliary cylinder, said latter valve being substantially cup shaped, having an opening in its bottom, a main piston movable in the main cylinder means carried by the main piston for allowing air to pass between the piston and the wall as the piston moves in one direction only, namely away from the auxiliary cylinder, an auxiliary piston movable in the auxiliary cylinder, a rod connecting the two pistons and passing through the opening in the cup shaped check valve, stuffing material disposed within the cup shaped valve about the rod, and means for holding the stuffing material in place.

In testimony whereof I affix my signature in presence of two witnesses.

FRANK JOHNSON.
